UNITED STATES PATENT OFFICE

JOHN G. CLEMENS, OF BUFFALO, NEW YORK, ASSIGNOR TO BUFFALO FUSE CORPORATION, OF BUFFALO, NEW YORK, A CORPORATION OF NEW YORK

FUSE

Application filed July 27, 1923. Serial No. 654,267.

This invention relates to a fuse and more particularly a fuse of the knife blade type in which the terminals are constructed in the form of knife-blade, or flat plate terminals adapted to fit corresponding sockets on the switch board.

Fuses of this character, as heretofore constructed, have been found objectionable on account of the liability of the fuse going to pieces or being seriously damaged when the fuse blows, also the liability of the flame passing through the fuse and setting fire to nearby objects, and also the cost of making the fuse and the inconvenience of refilling the same.

It is the object of this invention to provide a fuse which overcomes the various objections above enumerated and which is strong and durable and capable of being easily and quickly refilled with the new fuse link when required.

In the accompanying drawings:

Figures 1 and 2 are longitudinal sections taken at right angles to each other of a fuse embodying my improvements. Figures 3 and 4 are cross sections of the same taken on the correspondingly numbered lines in Figure 1. Figure 5 is an end elevation of the terminal ferrules of the fuse. Figure 6 is a fragmentary longitudinal section, on an enlarged scale, of the joint between the enclosing casing and one of the ferrules. Figure 7 is a cross section on line 7-7 of Figure 6. Figures 8, 9, 10, 11, 12 and 13 are detached perspective views of some of the parts of the fuse.

Similar characters of reference indicate like parts in the several figures of the drawings:

The frame of the fuse has the form of a tube 15 which is constructed of fiber or other suitable insulating material and is open at its opposite ends while one part of its side is provided with an inlet opening 16 through which the fuse link 17 is introduced into the frame and the fragments thereof after being blown are removed therefrom. Mounted in opposite ends of this tubular frame are the terminals 18, 19 of plate or knife blade form which are arranged out-

side of the frame and each of which is provided with an inwardly projecting tang 20 forming inwardly facing shoulders 21 on each of the blades at opposite edges of the same and its tang. The tang of each terminal projects inwardly into the central part of one end of the tubular frame and the two tangs are adapted to be connected within the frame by the fuse link so as to complete the electrical connection through the same. The outer parts of the two tangs pass through diametrical slots 22 formed in metal closure and supporting disks 23, 24, each of which engages its outer side with the shoulders 21 of the companion terminal 55 60 65 70 75 80 85 90 95 100 blade while its inner side engages with the adjacent outer end of the tubular frame. The disk 23 is preferably of the same diameter as the periphery of the tubular frame but the disk 24 is of larger diameter so that its marginal part forms an annular flange or shoulder, as shown in Figures 1 and 2, for a purpose which will presently appear. Arranged within each end of the tubular frame and engaging with the inner side of the adjacent supporting disk is a screen 25 which is preferably made up of a plurality of disks of woven wire which are assembled side by side and provided centrally with a slot 26 which receives the tang of the respective terminal blade while the peripheral edges of these screen disks engage with the bore of the tubular frame so as to produce a foraminous baffle across the entire end space within the frame. Adjacent to the inner side of each screen is arranged a retaining cup, the interior of which forms an expansion chamber for the gases resulting from the burning of the fuse link. The cylindrical body 27 of the cup engages its periphery with the bore of the tubular frame and its free outer edge with the inner side of the adjacent screen while the head 28 thereof at the inner edge of the body is provided with a slot 29 which receives the adjacent tang and forms with the screen a vent or relief chamber within this cup.

By arranging these screen disks at the end of the retaining cup instead of inside the cup as was heretofore done, the disks

can be made of greater diameter, so that they are less weakened by the slots therein which accommodate the tang 20 of the contact blade 19 and furthermore the gases in the cup can more readily flow through the screen since they act on practically the entire surface of the screen.

After the companion disk, screen and cup have been assembled on a tang the same are firmly held in place thereon by one or more fastening pins 30 passing transversely through the tubular frame cup and tang, as shown in Figures 1 and 2. Each of the supporting disks is provided with one or more longitudinal vent openings 31 in line with the uncovered part of the screen, and the cylindrical body of the adjacent cup and the respective part of the tubular frame are provided with one or more transverse vent openings 32, thereby placing this chamber within each cup in communication with the exterior of the fuse and also with the space around the frame thereof. The chambers formed in these cups permit the gases formed by the fusing of the fuse link 17 to expand and thus materially assist in cooling the gases before they pass through the screens 25.

Although the fuse link may be detachably connected with the tangs of the terminals in various ways this is preferably effected by fastening bolts passing with their shanks 34 through openings in the tangs and slots in the fuse link which rest on the tangs and bearing with their heads 35 against the outer side of the link through the medium of washers 36, while the threaded lower ends of the shanks of these bolts engage with nuts 38 on the underside of these shanks, as shown in Figure 1. Each of these nuts preferably has a flat face 40 which bears against the adjacent outer side of one of the retaining cups for the purpose of preventing this nut from turning when tightening or loosening the bolt and thus facilitating replacement of the fuse link.

In order to make the tubular frame as strong as possible and still permit of readily attaching the fuse link to the tangs and removing the remnants therefrom after the same has blown, the side opening of the tubular frame is extended about 90 degrees circumferentially around the same so that one longitudinal edge 41 of this opening is arranged in the same plane, or nearly so, as the upper surfaces of the tangs and the companion longitudinal edge 42 thereof is arranged in a plane which is parallel with or nearly so, the opposite longitudinal edge 43 of the tangs, as shown in Figures 1 and 4. By this means ample room is provided for applying a fuse link to and removing the same from the tangs by means of a screw driver or similar tool and at the same time leaving the maximum amount of

material circumferentially in the tubular frame so that the same is strong and durable and better able to withstand the internal pressure to which the same is subjected when the fuse link blows. The enclosing 70 casing or shell of the fuse comprises a tubular body 43 of fiber or other approved insulating material and two ferrules 44, 45 of metal applied to opposite ends of the body. Each of these caps has a cylindrical 75 body 46 which is secured around one end of the casing body and an inwardly projecting flange 47 arranged at the outer edge of the ferrule body. The flange of the ferrule 44 is permanently secured to the casing body 80 and adapted to engage with the outer side of the marginal part of the supporting disk 23. The flange 47 of the other ferrule 45 bears against the outer side of the disk 24 and is provided with notches 49 on diametrically opposite sides of its inner edge 85 which receive the longitudinal edge portions of the terminal blade 19 so as to prevent these parts from turning relatively to each other. The ferrule 44 is capable of 90 sliding on and off the terminal blade 18 but the ferrule 45 is limited in its longitudinal movement on the terminal 19 by any suitable means, such as by squeezing or pinching the metal on opposite longitudinal edges 95 of the terminal blade 19 so as to form lateral steps or projections 50 thereon which the flange of the ferrule 45 may engage to prevent these parts from being pulled apart, as shown in Figures 1 and 2.

The bodies of the ferrules may be connected with the body of the casing in any suitable manner but in the preferred construction the body of the ferrule 44 is rigidly connected by a screw joint 51, the cooperating threads of which are formed directly on the casing body and the body of the ferrule 44, while the casing body and the body of the ferrule 45 are detachably connected by a screw sleeve 52 of sheet 100 metal having an internal thread engaging with a corresponding thread on the casing body and an external thread engaging with an internal thread on the body of the ferrule 45, so as to permit of connecting and disconnecting the casing or cover with the last mentioned ferrule. In order to positively prevent the removable ferrule 44 from turning on the casing body a longitudinal dowel or pin 53 is applied 105 to these parts so as to extend across the screw joint between the same, as shown in Figure 1. For the purpose of preventing the screw sleeve from unscrewing from the casing body this sleeve is provided with 110 one or more punch marks, spurs, or pricks 48 which enter the casing body, as shown in Figure 6. The screw threaded connections between the ferrules or caps and the casing positively prevent any flame from 115

passing through the joints between the casing and the caps. The diameter of the bore of the cover or body of the casing is somewhat larger than the periphery of the tubular frame, so as to form an annular relief or vent passage or space 54 between these members which extends beyond the lateral vent openings 32, leading to the relief chambers in opposite ends of the tubular frame.

When the fuse link blows the flame and hot gases generated together with any particles of metal in molten or solid form; first pass laterally outwardly from the tubular frame through the opening 16 therein and then lengthwise toward opposite ends of the space 54 between the tubular frame and the casing. Upon striking the opposite ends of this space the flame and hot gases rebound and then pass transversely inwardly through the vent openings 32, into the relief or expansion chambers of the cups, thence longitudinally outwardly through the screen whereby the flame is extinguished, and thereafter only the gases under pressure pass lengthwise through the openings 31 to the outer atmosphere. The particles of metal, however, owing to their inertia, do not follow the gases through the vent openings 32 but strike the ends of the space 54 and remain there until the frame is taken out of the casing, whereupon these metal particles will readily drop out of the fuse casing. By means of this construction the metal cannot reach the screens 25, so that the fuse can be used repeatedly without having the screens become clogged. The gases therefore follow a tortuous path from the time they are generated until they leave the fuse whereby the pressure within the fuse is gradually relieved or deadened and the fuse is prevented from being damaged or impaired when the fuse link blows. In fuses of the construction described, the products of combustion are carried out through the opening 16 in the tubular frame and then into the longitudinal passage, instead of passing lengthwise of the fuse link, as in constructions heretofore used, and this action has a tendency to increase the resistance of the arc formed by the blowing of the fuse link and thus greatly decrease the effectiveness of the arc. These products of combustion seem to conduct current to a certain extent and consequently by leading the products of combustion away from the fuse link and out of the tubular frame, the force of the arc is greatly diminished.

When it is desired to refill, repair or inspect the fuse access to the interior of the same may be had for this purpose by turning the casing backwardly so as to unscrew the same from the respective ferrule which is fixed on the head after which the casing may be moved lengthwise of the frame or

uncovering the fuse inlet of the frame and the means for fastening the same to the tangs of the terminals.

As a whole this fuse is very simple in construction and efficient in operation. Furthermore the same meets the test of the severest requirements and is not liable to get out of order by repeated use. Moreover the same is capable of being manufactured economically on account of the absence of any expensive or delicate operations in its production.

I claim as my invention:

1. A fuse comprising a terminal blade having an inwardly projecting tang and an inwardly facing shoulder between said blade and tang, a disk arranged on said tang and engaging said shoulder and provided with a vent opening, a tubular frame surrounding said tang and engaging said disk, a plurality of layers of screening material arranged within said frame and engaging said disk so as to cover the vent opening therein, and a retaining cup having an imperforate end wall and openings in its side and arranged in said frame and engaging its open end with said screening material to compress said layers of screening material and to form a chamber into which gases enter laterally before passing through said screening material.

2. A fuse comprising a terminal blade having an inwardly projecting tang and an inwardly facing shoulder between said blade and tang, a disk arranged on said tang and engaging said shoulder and provided with a vent opening, a tubular frame surrounding said tang and engaging said disk, a screen arranged within said frame and engaging said disk so as to cover the vent opening therein, a retaining cup mounted on said tang within said frame and engaging its open end with said screen to form a chamber into which the gases enter before passing through said screen, an enclosing casing surrounding the frame but separated therefrom by an intervening passage, said frame and cup having an opening leading laterally from the interior of the cup to said intervening passage, and a pin passing through the frame, cup and tang.

3. A fuse having a casing adapted to contain a fuse link and having a passage therein into which the products of combustion resulting from the fusing of said link are adapted to pass, a second passage connected with said first passage and extending substantially transversely thereof, a chamber into which said transverse passage leads, and in which the gases discharged from said passage may expand, an outlet from said chamber, and metallic screening material arranged across said outlet.

4. A fuse including an enclosing casing, a tubular frame arranged in said casing

and adapted to support a fuse link and forming with said casing a longitudinal passage for products of combustion formed by the fusing of said link and having a lateral opening communicating with said passage, the ends of said frame being closed, a chamber supported by said frame and connected with said longitudinal passage by a transversely extending passage, and vent openings out of alignment with said transversely extending passages and through which products of combustion pass from said chamber.

5. A fuse including an enclosing casing, a tubular frame arranged in said casing and adapted to support a fuse link and forming with said casing a longitudinal passage for products of combustion formed by the fusing of said link and having a lateral opening communicating with said passage, the ends of said frame being closed, a chamber supported by said frame and connected with said longitudinal passage by a transversely extending passage, vent openings in said chamber, and screening material arranged beyond said chamber and through which gases pass from said chamber to said vent openings.

6. A fuse including an outer shell, a terminal having an inwardly projecting tang, forming an inwardly facing shoulder between the ends of the terminal, a transversely extending part secured with its outer side against said shoulder, a ferrule having means for releasably securing the same to an end of said shell and having an inwardly projecting flange adapted to exert pressure against said transversely extending part when said terminal is secured on said shell, and lateral projections on said terminal to engage said flange to permanently hold said ferrule on said terminal.

7. A fuse including an outer shell, a terminal having an inwardly projecting tang to which a fuse link may be connected, a transversely extending plate secured to said terminal and forming a closure for an end of said shell, a ferrule having means for releasably securing the same on said shell and having an inwardly projecting flange on the outer portions thereof adapted to exert pressure against said transversely extending plate when the terminal is secured on the shell, and lateral projections on said terminal to engage said flange to permanently hold said ferrule on said terminal.

8. A fuse including an outer shell, a frame removably arranged within said shell and spaced therefrom to form a longitudinal passage between said shell and frame, a fusible member mounted in said frame, a chamber arranged in an end of said frame and vented to the exterior of said fuse, and lateral passages connecting said chamber and an end of said longitudinal passage

and constituting the sole means for conducting products of combustion from said longitudinal passage to said chamber, the removal of said frame from said shell rendering said end of said longitudinal passage accessible to remove solid products of combustion therefrom.

9. A fuse including an outer shell, a frame arranged within said shell and forming with said shell a passage extending lengthwise of the fuse, chambers in the opposite ends of said frame and vented to the exterior of said fuse, lateral passages connecting said chambers and said lengthwise passage in the ends of said passage, and a fusible member arranged within said frame and constituting the sole means for conducting products of combustion from said longitudinal passage to said chambers, said frame being removable in a unit from said shell to render the ends of said longitudinal passage accessible for removal of solid products of combustion therefrom.

10. A fuse including an outer shell, a frame arranged within said shell and forming with said shell a passage extending lengthwise of said shell, chambers in the opposite ends of said frame and vented to the exterior of said fuse, lateral passages connecting said chambers and said lengthwise passage near the ends of said passage, terminals extending beyond the ends of said frame and secured to said frame, a fusible member arranged within said frame and connected with said terminals, the terminal at one end of said frame being arranged to pass through one end of said shell when said shell is placed into operative position about said frame, and a ferrule on the other end of said frame provided with releasable means for securing said frame to said ferrule.

11. A fuse including an outer shell, a frame arranged within said shell and forming with said shell a passage extending lengthwise of said shell, chambers in the opposite ends of said frame and vented to the exterior of said fuse, lateral passages connecting said chambers and said lengthwise passage near the ends of said passage, terminals extending beyond the ends of said frame and secured to said frame, a fusible member arranged within said frame and connected with said terminals, the terminal at one end of said frame being arranged to pass through one end of said shell when said shell is placed into operative position about said frame, a ferrule arranged at the other end of said fuse and permanently secured in place between said end of said frame and a projection of the other terminal, and interengaging means on said ferrule and said frame for securing said ferrule to said frame.

12. A fuse including an outer shell, a frame arranged within said shell, a terminal

having an inwardly extending part secured to said frame, a ferrule adapted to be releasably secured to said shell and having a recess through which said terminal extends, and a projection on said terminal extending beyond the recess in said ferrule to prevent removal of said ferrule from said terminal.

13. A fuse including an outer shell, a frame arranged within said shell and movable lengthwise into and out of said shell, terminals secured to the ends of said frame, one of said terminals being arranged to move through said shell into its operative position, a fuse link arranged on said shell and connected with said terminals, a ferrule permanently mounted on the other terminal, and means on said ferrule and an end of said shell for releasably securing said ferrule to said shell.

14. A fuse including an outer shell, a frame arranged within said shell and movable lengthwise into and out of said shell, terminals secured to the ends of said frame, one of said terminals being arranged to move through said shell into its operative position, a fuse link arranged on said shell and connected with said terminals, a ferrule having an opening therein through which the other terminal extends, a projection on said other terminal for preventing removal of said ferrule therefrom, and means for releasably connecting said ferrule with an end of said shell.

In testimony whereof I affix my signature.

JOHN G. CLEMENS.
